UNITED STATES PATENT OFFICE

172,384

AWNNG

Andrew F. Dynda, Detroit, Mich.

Application February 16, 1953, Serial No. 23,647

Term of patent 14 years

(Cl. D21—6)

To all whom it may concern:

Be it known that I, Andrew F. Dynda, a citizen of the United States of America, residing in Detroit, county of Wayne, State of Michigan, have invented a new, original, and ornamental Design for an Awning, of which the following is a specification, reference being had to the accompanying drawing, forming a part hereof.

Fig. 1 is a perspective view of an awning, showing my new design.

Fig. 2 is a side elevational view thereof.

I claim:

The ornamental design for an awning, as shown.
